[57] CLAIM

The ornamental design for an exercise treadmill, as
shown and described.

DESCRIPTION

FIG. 1 is an elevational view of one side of an exercise
treadmill showing my new design;

FIG. 2 is an elevational view of the other side of the
exercise treadmill as shown in FIG. 1;

FIG. 3 is a front elevational view of the exercise tread-
mill shown in FIG. 1;

FIG. 4 is a rear elevational view of the exercise tread-
mill shown in FIG. 1;

FIG. 5 is a top plan view of the exercise treadmill
shown in FIG. 1;

FIG. 6 is a bottom plan view thereof; and,

FIG. 7 is a perspective view thereof.

FIG. 1

FIG. 2
